UNITED STATES PATENT OFFICE.

HAROLD A. WEBSTER, OF HAVERHILL, ASSIGNOR TO GEORGE H. P. FLAGG,
OF BOSTON, MASSACHUSETTS.

CLEANING AND POLISHING BRUSH.

SPECIFICATION forming part of Letters Patent No. 449,239, dated March 31, 1891.
Application filed September 20, 1890. Serial No. 365,638. (No model.)

To all whom it may concern:

Be it known that I, HAROLD A. WEBSTER, of Haverhill, in the county of Essex and State of Massachusetts, have invented certain new and useful Improvements in Cleaning and Polishing Brushes, of which the following is a specification.

This invention has for its object to provide a brush adapted particularly to clean the surfaces of boots or shoes, to remove from the upper-leather the stains and marks incidental to the operations involved in the manufacture of the goods, and to impart to said surfaces a desirable polish or finish.

15 The invention consists in a brush composed of a series of sheets or pieces of cloth or other suitable flexible material attached at their inner edges to a movable support or holder, which may be either a cylinder or a belt adapted to move on pulleys, the said pieces being arranged at right angles to the direction of movement of the support, so that they present continuous brushing-surfaces extending across the path in which the support moves.

25 In the accompanying drawings, forming a part of this specification, Figure 1 represents a perspective view of a cylindrical brush embodying my invention. Fig. 2 represents a perspective view of a portion of the brush. 30 Fig. 3 represents an enlarged sectional view of a portion of the same. Fig. 4 represents an edge view of the brush formed as a belt.

The same letters of reference indicate the same parts in all the figures.

35 In carrying out my invention I attach to a flexible band *a*, of cloth, leather, or other suitable material, a series of brush-strips *b*, which act with the desired cleaning or polishing effect on a boot or shoe upper or other article presented to the brush. I prefer to make said strips of cloth, either cotton or woolen; but they may be of chamois-skin or other suitable material.

45 The brush-strips *b* are attached at their inner edges to the band *a* by stitches *c*, Fig. 3, or other suitable fastenings, and are arranged so that they stand side by side, their outer edges being parallel and arranged crosswise of the path in which the band *a* moves when the brush is in operation. Each strip *b* is secured at its inner end in a flat condition or

along a straight line to the hub or carrier that supports it. The outer edge of each piece is therefore so held or confined that it cannot sway about in all directions, or, in other words, it cannot move to any material extent in a direction parallel with the shaft on which it rotates. The band is preferably glued or otherwise securely attached to the periphery of a cylinder or pulley *d*, the brush-strips radiating from the periphery of the pulley and having their free outer edges arranged parallel with the axis of the pulley, as shown in Fig. 1.

It will be seen that when the pulley is rapidly rotated the free edges of the brush-strips, forced outwardly by centrifugal force and extending continuously across the path in which the brush moves, constitute a brush which is sufficiently yielding to conform to the curvatures of the surface of a boot or shoe or other article presented to the brush, and at the same time the continuous edges of the brush-strips present sufficient resistance to prevent the article from sinking too deeply into the brush. The strips, arranged as described, with their free edges extending across the path in which the brush moves, differ in their effect from flexible strips or disks as used in an ordinary rag-wheel, in which the strips are arranged edgewise to the path in which the brush moves. Said rag-wheel strips are separable by the pressure of the work against the periphery of the brush, so that the continuity of the brushing-surface across the path in which it moves is liable to be broken in the rag-wheel. In my improved brush, however, the continuity of the brushing-surface cannot be broken crosswise of the path of movement of the brush, because the edges of the brush-strips extend in my brush at right angles to the direction in which they extend in the rag-wheel. Hence the pressure of the article against the wheel is opposed by the entire outer edge of each strip.

If desired, the band *a* may be made in the form of an endless belt, as shown in Fig. 4, said belt being supported when in use by pulleys *q q*. In this case the strips *b* will of course be arranged so that their outer edges extend across the path of movement of the brush.

I do not limit myself to the use of a band *a* when the strips *b* are supported by a single pulley, as in such case the strips may be attached directly and independently to the pulley without being first attached to the band.

I claim—

1. A brush composed of a series of flat leaves or sheets forming brush-strips of flexible material and a movable holder to which the inner edges of said leaves or sheets are attached, the outer edges thereof being arranged substantially at right angles to the direction of movement of the brush, as set forth.
- 15 2. The improved brush composed of a cylinder or pulley and the series of brush-strips, consisting each of a continuous sheet of flexible material attached to the periphery of the pulley and radiating therefrom, the free outer

edges of said strips being substantially parallel with the axis of the cylinder and substantially at right angles to the direction of motion of the brush, as set forth.

3. The improved brush herein described, composed of a series of brush-strips, which consist each of a continuous flat leaf or sheet having its inner angular or bent edge attached to a hub or carrier and arranged parallel with each other, substantially as set forth.

In testimony whereof I have signed my name to this specification, in the presence of two subscribing witnesses, this 11th day of September, A. D. 1890.

HAROLD A. WEBSTER.
